DESIGN FOR A JUVENILE VEHICLE

William I. Smith, Goshen, Ind., assignor to The Hetrick Manufacturing Company, Toledo, Ohio, a corporation of Ohio

Application July 14, 1943, Serial No. 110,667

Term of patent 7 years

(Cl. D34—15)

To all whom it may concern:

Be it known that I, William I. Smith, a citizen of the United States and a resident of Goshen, Elkhart County, Indiana, have invented a new, original, and ornamental Design for a Juvenile Vehicle, of which the following is a specification, reference being had to the accompanying drawings, forming a part thereof.

In the drawings:

I claim:

The ornamental design for a juvenile vehicle, as shown.

WILLIAM I. SMITH.
